Primary Examiner — Lauren R Calve(74) *Attorney, Agent, or Firm* — Kirk A. Buhler; Buhler & Associates Patenting(57) **CLAIM**

The ornamental design for a grip for a wire handle, as shown and described.

DESCRIPTION

FIG. 1 is a bottom side perspective view for a grip for a wire handle showing my new design;

FIG. 2 is a bottom plan view thereof;

FIG. 3 is a top plan view thereof;

FIG. 4 is a front elevation view, the rear elevation view being a mirror image thereof;

FIG. 5 is a front sectional view taken along lines 5-5 from FIG. 3;

FIG. 6 is a left elevation view, the right elevation view being a mirror image thereof;

FIG. 7 is a left sectional view taken along lines 7-7 from FIG. 3; and,

FIG. 8 is a top side perspective view thereof.

1 Claim, 8 Drawing Sheets---
